UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

MACHINE FOR DELIVERING MAGAZINES AND THE LIKE.

1,392,471.

Specification of Letters Patent.

Patented Oct. 4, 1921.

Original application filed September 7, 1910, Serial No. 580,870. Patent No. 1,232,639, dated July 10, 1917. Divided and this application filed June 29, 1917, Serial No. 177,652. Renewed April 15, 1921. Serial No. 461,677.

To all whom it may concern:

Be it known that I, HENRY A. WISE Wood, a citizen of the United States, residing at New York, in the county of New York and State of New York, have invented a new and useful Machine for Delivering Magazines and the like, of which the following is a specification.

This is a division of my Patent No. 10 1,232,639, granted July 10, 1917, on a machine for making magazines and the like filed Sept. 7, 1910, Serial No. 580,870.

This invention relates to the art of delivering books, magazines, and newspapers 15 which are made up of several signatures, varying in character of paper and number of pages.

The principal objects of this invention are 20 to provide a magazine, book, or newspaper making machine with an improved feeding and delivery device constructed and arranged to deliver a whole magazine, book or newspaper at a single operation. The invention also involves improvements in combinations 25 of parts and details of construction as will appear.

Reference is to be had to the accompanying drawings, in which—

Figure 1 is a diagrammatic side view of a 30 magazine making machine constructed in accordance with this invention;

Fig. 2 is a side view of the delivery;

Fig. 3 is an end elevation thereof;

Fig. 4 is a plan of a portion of the gathering drum showing delivery mechanism adjacent thereto;

Fig. 5 is a diagrammatic side view showing another form of gathering device that can be used in place of that shown in Fig. 1.

40 As has been stated this invention has been made so that practically a whole magazine, or the like, may be delivered at a single operation. The whole book is produced at a single operation, so to speak, and it is delivered immediately ready for sale, at a very high rate of speed. The several features of the invention center about a gathering device R, shown in Fig. 1, in the form of a large rotating drum. This is usually made of a 45 width equal to the length of one of the pages to be printed, but may be double width, in which case some other elements are made double width. It may be considered that

part of the rest of the mechanism is for printing, and performing other operations 55 upon signatures or sheets, and feeding them to this drum, and other parts for removing the product from it, gathering it into a bundle and completing the magazine or the like.

The press as shown consists of one or more 60 decks arranged on one or both sides of the gathering device. Fig. 1 shows a four deck web printing press A¹, A², A³, A⁴, provided with any desired or usual kind of inking mechanism B, B', operating in the usual or 65 any well known way. Any number of presses can be arranged around the gathering device and a second one A⁵ is indicated in dotted lines. If desired also the press or 70 presses can be located in this dotted line or any other convenient position instead of the full line position. The decks are intended to deliver all of their printed products to the gathering device R.

The cylinders C of this press are divided 75 up having a plurality of plates both longitudinally and circumferentially. For the purpose of illustration each of these plate cylinders may be provided with thirty-two plates arranged in four circles of eight plates 80 each, that is, each cylinder has four plates along the cylinder and eight around it. These can all be original plates in some cases or two sets of duplicate ones in others. With this arrangement each press can be made to 85 print thirty-two impressions on a web at each revolution. The web, having four impressions across it, is slit to form four webs. It will be understood of course that plate cylinders having different arrangements of 90 plates can be used to print a smaller or larger number of pages and that any kind of inking mechanism is employed so as to print in black or colors as desired.

Located adjacent to the plate cylinders C 95 are slitting devices D each having slitting cutters opposite circumferential spaces between the plates. Each deck also is provided with turning bars E, so as to cross and associate the webs and bring them to a one-page width or two-page width as desired. With a space between these narrow webs this allows two similar or different magazines to be delivered at the same time.

In the form shown in Fig. 1, the upper 105 and lower deck A' and A⁴ are shown as ar-

ranged to produce four webs each, and mechanism is provided by which after these webs are associated by the turning bars so as to come one over the other they can all be 5 passed to the drum R in a plurality of ways. However, as illustrated, one of the webs from the upper deck is omitted so that only three signatures are being produced by that deck. This shows how the machine can be 10 used for magazines of various make-up. The lower and upper decks in the arrangement shown are delivering to the gathering drum four page signatures from four of the cutting, collecting, and folding devices F. 15 The two center decks A² and A³ are shown delivering eight-page signatures from two cutting, collecting and folding devices F. It will be understood of course that if the magazine requires a different number or 20 sizes of signatures of this kind at this point the presses will be run in a different way, as for example, each of the center decks may run its webs to one of the devices F or some of the webs may be omitted altogether if 25 that is required by the conditions. In that case one or more of the collecting devices F will be idle.

The combined cutting, collecting and folding devices can be constructed as is now 30 common in this industry. It will be understood, of course, that a plurality of elements are located along the operating surface of the gathering device to take the signatures from the several printing machines or decks 35 and deliver them to the gathering device which takes them up and delivers them in the proper order to the delivery cylinder which will be described hereinafter.

In addition to what has been described it 40 is to be understood that the presses or decks referred to need not be of the same character, as it is one express purpose of this invention to provide for using many types of printing presses in the same machine. In 45 this character of work it is common to use both flat sheet bed and rotary web presses, and it is preferred that the ordinary high-speed web presses be employed for the work that has been described above, and that flat 50 presses be employed for the kind of work that has to be done more carefully and accurately and at a slow speed, while a less high grade of work may be done by a press designed for the purpose.

55 Whatever form of press is used for producing the main product and the ordinary signatures of the magazine, and whatever inserts and smaller signatures, it will be obvious from consideration of Fig. 1 that 60 these various products will be delivered one by one to the gathering drum R in a pre-determined order, and that during a complete revolution thereof the entire magazine will be applied to it, except the cover. The 65 next step in the operation of this machine

is to deliver this product, making the least possible number of alterations in the ordinary delivery device, so that the entire magazine is produced by the machinery without handling the signatures or even the 70 stapled product. For this purpose I have shown a delivery device P (Figs. 2, 3 and 4) involving a delivery member in the form of a cylinder p having pins p' and a stripper p² for taking individual portions of the 75 product from the gathering drum. This delivery device is shown as provided with an endless chain mechanism p³ having hooks p⁴ on the delivery side thereof which receive the several signatures, inserts, or the 80 like, one by one, preferably, back of a guide p⁵. The endless chain travels downwardly on its delivery side and the hooks support the signatures and inserts so as to lower them on a support p⁶ which projects out between 85 the strands of the chain so that the signatures and sheets are left upon it as the hooks descend. A plunger p⁷ is then brought up automatically, by mechanism not herein shown in full, so as to push the signatures or the like 90 back in the collating device p⁸ of which the support p⁶ forms the bottom. They are held in place by hooks p⁹. Periodically, that is, when the material for a complete magazine has been introduced into the collating box, 95 the bottom p⁶ is shifted so as to allow the whole bunch of sheets and signatures to drop down between guides p¹⁰ where they are held firmly in position and are stapled by a 100 stapling device p¹¹ not shown in detail. Then by other automatic mechanism the bottom p¹² of this box is withdrawn so as to permit the stapled inside of the magazine to fall down between nipping rolls p¹³ where it 105 engages a cover which has been fed in from the side. This cover is fed in from a cover board q by nipping rolls q' controlled by a feed gage q² and is taken by tapes to the guides q³ in a well known way. In passing 110 to these guides it receives paste from a pasting device q⁴ so that when the nipping rolls p¹³ feed the bottom of the magazine down the pasted portion of the cover comes under the back of the inside. Both are drawn down through the lower nipping rolls p¹⁴ 115 into a delivery box p¹⁵ which is provided with a plunger p¹⁶ working in a well known way. In this way the completed magazines are delivered one at a time, or if the machine is set up double, two at a time, without the intervention of any hand manipulations and without even having the parts carried from one place to another by hand or human agency of any kind.

Although the gathering device has been 125 referred to and shown throughout as a drum, it will be understood that other types of gathering devices can be employed. One of them as shown in Fig. 5. In this figure the main presses can be the same as hereto- 130

fore described, but their cutting, folding and delivery mechanisms are arranged along one or both sides of the gathering device in a straight line. The latter consists of a 5 pair of chains r^{10} having grippers r^{11} or the like for taking the signatures from the guides of the folding devices. They pass the latter through guides r^{12} which take them to a delivery which can be of the same 10 character as that already described.

While I have illustrated and described only one form of the invention and of different parts thereof, I am aware that many 15 modifications can be made and that as far as most of the features of the invention are concerned, they do not depend upon the details of construction. Therefore I do not wish to be limited to the details of construction shown, except as expressed in the 20 claims, but what I do claim is:—

1. In a delivery, the combination of a delivery member for receiving the sheets and signatures to be delivered, a traveling conveyer having means thereon in position 25 to receive each sheet or signature as it passes over the delivery side of the delivery member to support the same, a collating box having a reciprocating bottom past which the conveyer is adapted to move 30 and normally projecting out into position to extend under the sheets and signatures as they are lowered, means for collecting a plurality of bundles of sheets or signatures in the collating box, and means for periodically 35 withdrawing said bottom to permit said bundles of sheets and signatures to drop from the collating box.

2. In a delivery, the combination of a delivery cylinder having pins for receiving the sheets and signatures to be delivered, a traveling conveyer having hooks therein in position to receive each sheet or signature from the pins as it passes over the delivery 40 side of the cylinder to support the same, a 45 guide for holding the sheet or signature in position to rest on the hooks, and a collating box below the guide having a bottom past which the conveyer is adapted to move and projecting out into position to extend 50 under the sheets and signatures as they are lowered on the hooks, whereby as each set of hooks descends below said bottom a sheet or signature will be deposited thereon.

3. In a delivery, the combination of a delivery cylinder having means for receiving the sheets and signatures to be delivered, a traveling conveyer to receive each sheet or signature as it passes over the delivery side of the cylinder, a guide for holding the sheet or signature in position, a collating box below the guide having a bottom past which the conveyer is adapted to move and projecting out into position to extend under the sheets and signatures as they are lowered 55 and having means for collating the sheets 60

and signatures into a bundle and discharging them without changing their direction of travel.

4. In a delivery, the combination of a delivery cylinder for receiving the sheets and signatures to be delivered, a traveling conveyer having means thereon in position to receive each sheet or signature as it passes over the delivery side of the cylinder, a collating box having a bottom past which 70 the conveyer is adapted to move and projecting out into position to extend under the sheets and signatures as they are lowered, whereby as each sheet or signature descends it will be deposited thereon, and 75 means for pushing back the sheets and signatures in bundles in the collating box.

5. In a delivery, the combination of a conveyer to receive each sheet or signature, a collating box having a bottom past which 80 the conveyer is adapted to move and in position to extend under the sheets and signatures as they are lowered, means for collecting a plurality of bundles of sheets or signatures in the collating box, means for 85 periodically withdrawing said bottom to permit said bundles of sheets and signatures to drop from the collating box, and means for receiving said bundles.

6. In a delivery, the combination of a delivery cylinder for receiving the sheets and signatures to be delivered, a traveling conveyer having hooks thereon in position to receive each sheet or signature as it passes over the delivery side of the cylinder 100 to support the same, a guide for holding the sheet or signature in position to rest on the hooks, a collating box below the guide having a bottom past which the conveyer is adapted to move and projecting out into 105 position to extend under the sheets and signatures as they are lowered on the hooks, means for collecting a plurality of bundles of sheets or signatures in the collating box, means for periodically withdrawing said 110 bottom to permit said bundles of sheets and signatures to drop from the collating box, and means below the same for receiving said bundles.

7. In a delivery, the combination of a delivery for receiving the sheets and signatures to be delivered, a traveling conveyer to receive each sheet or signature, a guide for holding the sheet or signature in position, a collating box below the guide having a bottom past which the conveyer is adapted to move and in position to extend under the sheets and signatures as they are lowered, means for collecting a plurality of bundles of sheets or signatures in the collating box, means for periodically withdrawing said bottom to permit said bundles of sheets and signatures to drop from the collating box, and means for receiving 115 said bundles.

- 4
8. In a delivery, the combination of a delivery member for receiving the sheets and signatures to be delivered, a traveling conveyer having means thereon to receive each sheet or signature as it passes over the delivery side of the delivery member, a bottom past which the conveyer is adapted to move and projecting out into position to extend under the sheets and signatures as they are lowered, whereby as each sheet or signature descends to said bottom, it will be deposited thereon, means for periodically withdrawing said bottom to permit the sheets and signatures to drop, means for receiving them, the last named means having a reciprocating bottom, means over the last named bottom for stapling the bundles, and means below said bottom for feeding the stapled bundle down when the last named bottom is withdrawn.
9. In a delivery, the combination of means for receiving the sheets and signatures to be delivered, a traveling conveyer having means thereon to receive each sheet or signature as it passes over said means, a bottom past which the conveyer is adapted to move and in position to extend under the sheets and signatures as they are lowered, whereby as each sheet or signature descends to said bottom, it will be deposited thereon, means for periodically withdrawing said bottom to permit the sheets and signatures to drop, means for receiving them, the last named means having a reciprocating bottom, and means for feeding the bundle down when the last named bottom is withdrawn.
10. In a delivery, the combination of means for receiving the sheets and signatures to be delivered, a traveling conveyer having means thereon to receive each sheet or signature as it passes over said means, a bottom past which the conveyer is adapted to move and in position to extend under the sheets and signatures as they are lowered, whereby as each sheet or signature descends to said bottom, it will be deposited thereon, means for periodically withdrawing said bottom to permit the sheets and signatures to drop, means for receiving them, the last named means having a reciprocating bottom, and means for feeding the stapled bundle down when the last named bottom is withdrawn.
11. In a delivery, the combination of means for receiving the sheets and signatures to be delivered, means to receive each sheet or signature as it passes over said means, a bottom in position to extend under the sheets and signatures as they are lowered, whereby as each sheet or signature descends it will be deposited thereon, means for periodically withdrawing said bottom to permit a bundle of sheets and signatures to drop, a second reciprocating bottom for receiving them, means for stapling the bundles, and means for feeding the stapled bundle down when the last named bottom is withdrawn.
12. In a delivery, the combination of a traveling conveyer, a collating box having a bottom past which the conveyer is adapted to move and projecting out into position to extend under the sheets and signatures as they are lowered thereon, means for periodically withdrawing said bottom to permit said sheets and signatures to drop from the collating box, a second reciprocating bottom below the same for receiving them in bundles, means over the last named bottom for stapling the bundles, means below said bottom for feeding the stapled bundle down when the bottom is withdrawn, and means for feeding covers under the last named bottom and for applying paste thereto, whereby said covers will be fed forward with the bundles.
13. In a delivery, the combination of a traveling conveyer, a collating box past which the conveyer is adapted to move and projecting out into position to extend under the sheets and signatures as they are lowered thereon, means to permit said sheets and signatures to drop from the collating box in bundles, a reciprocating bottom below the same for receiving said bundles, means over the bottom for stapling the bundles, means below said bottom for feeding the stapled bundle down when the bottom is withdrawn, and means for feeding covers under the last named bottom and for applying paste thereto, whereby said covers will be fed forward with the bundles.
14. In a delivery for magazine making machines, the combination of means for receiving bundles of sheets and signatures having a reciprocating bottom, means over the bottom for stapling the bundles, means below said bottom for feeding the stapled bundle down when the bottom is withdrawn, means for feeding covers under the bottom and for applying paste thereto, whereby said covers will be fed forward with the bundles, means for feeding the collected bundles and covers downward, means for receiving the same, and means for periodically pushing the completed magazines forward out of the way of those which are entering the same receiving means.
15. In a machine of the character described, the combination of a pair of endless chains movable longitudinally, a series of devices carried by the endless chains for receiving sheets or signatures and carrying them along by the chains, a plurality of devices arranged adjacent to the chains for feeding a plurality of sheets or signatures thereto, and means for delivering said sheets or signatures from the chains one at a time and collecting them.
16. In a machine of the character de-

scribed; the combination of a pair of endless chains arranged parallel with each other and each one adapted to move longitudinally, the adjacent strands of the two chains being movable in the same direction, means on said chains for receiving a plurality of sheets or signatures each at a

different point along the chain, and means located adjacent to said strands of the chains for delivering the sheets and signatures 10 from both of them and collecting the same.

In testimony whereof I have hereunto affixed my signature.

HENRY A. WISE WOOD.
